SPRAY GUNS

Floyd J. Kavanaugh, Galveston, Tex., assignor of fifty per cent to Clarke & Courts Investment Company, Houston, Tex.

Application February 8, 1954, Serial No. 408,797

11 Claims. (Cl. 299—88)

This invention relates to spray guns and more particularly to such guns of the compressed air atomization type constructed and arranged so that changes of spray gun material may be made instantly without the need for cleaning any part of the gun or spray material container.

It is a general object of the present invention to provide a novel and improved spray gun fitted with interchangeable spray material containers.

More particularly it is an object of this invention to provide a spray gun having a handle, air control and air jet parts incorporated into one unit and having one or more spray-liquid containers each incorporating a liquid nozzle together with means interfitting with the first unit to automatically effect operating relationship of the nozzle and jet for proper spraying.

An important object of the present invention resides in the provision of a spray gun in which no parts whatever require cleaning when changing from one material to another or from one color paint to another.

Another important object of this invention resides in the provision of a spray gun for paints or the like in which a separate container is provided for each different color or density of paint or the like and each is provided with an upwardly directed nozzle extending above the container cover for cooperation with the gun proper which handles air only whereby no parts need cleaning on changing colors or materials.

An important feature of the invention consists in the arrangement for interchangeably attaching the several containers to the gun unit whereby proper relationship of liquid nozzle and air jet is insured.

A further feature of the invention consists in the provision of means to adjust the liquid nozzle toward or away from the air jet.

A still further feature of the invention resides in the provision of quick adjustment means for raising or lowering the axis of the air jet in respect to the tip of the liquid nozzle.

Other and further objects and features of the invention will be more apparent to those skilled in the art upon a consideration of the accompanying drawing and following specification wherein is disclosed a single exemplary embodiment of the invention with the understanding that such modifications may be made therein as fall within the scope of the appended claims without departing from the spirit of the invention.

In said drawings:

Fig. 1 is a side elevation of a spray gun constructed in accordance with the present invention, the attached liquid container being broken away below the cover thereof;

Fig. 2 is a central vertical section through the apparatus shown in Fig. 1 and illustrating the air and liquid flow passages, the adjustments and the like; and

Fig. 3 is a front elevation of the forward portion of the spray gun unit further illustrating the adjustment features.

Spray guns making use of compressed air take many

2

forms and are used for a wide variety of purposes, including the application of paints, varnishes and similar coatings, the dissemination of insecticides, fungicides and similar materials, and in many of the arts and industries for the application of various liquids and suspensions.

The more or less standardized forms of compressed air spray guns divide into two general classes, first the truly industrial type in which both the air and the liquid are supplied through hoses, which type finds its principal advantage where continuous use with the same color of coating or the same liquid takes place for a number of hours. With this type of gun both the liquid and air pass through passages in the principal parts thereof and at least the fluid passages must be cleaned carefully before changing to another material, color, consistency or the like of sprayed fluid. The second form also passes the air through passages in the principal parts of the gun and picks up the liquid from a container attached to and carried by the gun. Most of these have an eduction tube passing through at least a portion of the gun mechanism to bring the liquid into proximity to the air jet for proper atomization. If the liquid is to be changed the container must be thoroughly cleaned with a solvent and a quantity of this solvent must be sprayed through the gun to clean out the passages leading to and through the fluid nozzle.

For many uses such guns are admirable, but where the type of fluid must be changed often, where it is highly volatile, or quick changes in consistency or color are necessary for blending or the like the requirement for cleaning of the several parts before each change is not only laborious but time consuming and wasteful of material. It is therefore the purpose of the present invention to provide a spray gun which may be divided into two general parts, the first being the principal body unit including the handle, the air passage, a trigger actuated air control valve and the air jet, while the second unit, which is usually supplied in multiple, includes a spray liquid container, a liquid nozzle connected thereto and means for attaching this unit to the principal unit of the gun. Thus by having a plurality of containers, each with a different liquid, changes can be made instantly since no liquid passages need cleaning, each nozzle and its connecting passages remaining with its container allotted to a specific liquid. Mechanism is provided to insure proper relationship of the axes of jet and nozzle, and adjusting means are available for actuation without stopping the spray operation. This type of gun is extremely useful to painters doing touching up or repair work on vehicles, office furniture, machines and the like, and in fact any place where frequent changes of sprayed fluid or color are necessary.

Referring now to the drawing, it will be seen that the principal unit of the gun takes a more or less conventional form, having the usual handle 10 shaped somewhat like that of an automatic pistol. Conveniently the main air passage 11, extends longitudinally through the handle and terminates at the lower end in the nipple 12 to which an air hose may be attached. At the upper end of the passage it is intersected by the valve body 13 extending through the upper part of the handle, and having the movable valve disc 14, its actuating plunger 15 and closing spring 16 all of more or less conventional form and operating in an obvious manner. A bore 17 connects the space behind the valve disc 14 with the passage 11, while a second bore 18 connects the valve outlet to the threaded counterbore 19 extending through the top surface of the handle unit. Forward of this the split lug 20 provides for mounting the hinge pin for trigger 21 positioned to engage the exposed forward end of valve stem 15 and press the valve open when the trigger is squeezed.

60

65

70

A plate 22 is mounted against the top of the handle and held in position by means of flange nut 23 screwed onto plug 24 engaged in the threads of the counterbore. Suitable means such as the downturned rear flange hold the plate against relative rotation on the top of the handle and augment the frictional engagement of the flanged nut. The plug 24 may have a suspension ring 25 provided at its upper end for hanging the gun if desired. Longitudinal passage 26 in the plug connects to the handle passage 18. Formed integral with plate 22 or attached thereto by screws or rivets, as shown, is the tubular forward projecting stem 28 of the principal unit of the gun. This extends a convenient distance beyond the trigger so that the fluid reservoir later to be described will not interfere with the operator's finger on the trigger. This extension 28, forming part of a pin and socket connection, is bored from its outer end toward the handle to provide a uniform diameter bore 29 having a pin 30 extending transversely thereof adjacent its rear end.

The enlarged outer end or head 31 on the stem has a cylindrical outer surface to receive the fitting 32 shown in all three figures. This latter is a thick roughly triangular plate bored to fit closely over the surface of the head 31 and adapted to be mounted thereon and held in position by means of a set screw or the like, such as shown at 33 in Fig. 1, threaded into a bore in the fitting and arranged to engage the surface of the head to lock the two in proper position. Alignment is effected conveniently by having the inner end 34 of screw 35 which is threaded into a diagonal bore in the fitting extend closely through a non-threaded opening properly oriented in the head 31. This screw 35 has a large knurled head for a purpose which will later appear.

In vertical alignment with the bore 29 the fitting is provided with a vertically disposed slot 37 having parallel side walls providing a relatively close working fit for the metal tube 38 or jet which extends therethrough. This tube is provided with a suitable fine bore shaped and sized to regulate the issuing air used for atomizing the liquid. The rear end of the jet behind the fitting 32 is either integral with, threaded or otherwise attached to a slightly flexible tube 40, as by means of a fitting 41. This tube 40 has its rear end enlarged and threaded for reception in a bore 43 formed laterally in the plug 24 and intersecting the bore 26 therein. In this manner air is conducted to and through the jet whenever the trigger is pressed.

A small helical spring 45 with one end received in a recess at the bottom of slot 37 serves to bias the nozzle tube 38 toward the top of the slot. This provides then for movement of the nozzle tube in a vertical plane under the action of its adjusting screw 46 threaded in the upper portion of fitting 32 just above the slot and having a rounded end bearing on the jet to move it up or down as the knurled head is rotated.

The above parts complete the first or air unit of the gun. The second or liquid unit may be provided in any desired number, each complete, as now about to be described. Such a unit includes a mounting stem or plug 50 adapted to have a close sliding fit in the bore 29 in the end of the stem or stock 28 of the air unit of the gun. The rear end of this stem is transversely slotted as at 51 to closely fit over the pin 30 to insure against relative rotation of the units when the stem is inserted the proper distance.

The stem or plug 50 is preferably formed integral with head 52 having a passage 53 therein normal to the plug axis. The upper end of 53 receives a threaded fluid nozzle 54, which has a suitably calibrated bore 55 to pass the desired quantity of liquid for the spray. The nozzle is of such a height as to have its bore terminate within the range of adjustment of the axis of the jet tube. The lower end of passage 53 threaded receives the liquid pickup tube 58 which depends therefrom. It is of such a length as to reach substantially to the bottom of the

desired size container, such as 60, whose upper edge is threaded as at 61 to engage into the threads of the skirt of vented and centrally perforated cover 62 mounted on the externally threaded lower portion of the head 52 and clamped between collar 63 engaging its upper surface and the nut 64 its lower surface.

This liquid unit is complete as just described and can be quickly mounted or dismounted from the air unit by manipulation of the screw 35 and insertion or withdrawal of the plug from the socket. The act of assembling the parts insures proper vertical alignment of the axis of the liquid nozzle and its horizontal relation to the jet tip to change the character or density of the spray is regulated by the amount the plunger is inserted in the socket. When the proper position is found screw 35 is tightened. Further adjustment of the character, shape and the like of the spray is effected by manipulation of the screw 46 which regulates the vertical height of the horizontal axis of the air jet in relation to the tip of the liquid nozzle.

In use, the liquid desired to be sprayed is placed in one of the containers 60 and the plug of the unit inserted in the socket of the air unit of the gun and proper adjustments of the relative positions of the nozzle and jet made as just described. Thereafter the gun is used in the normal manner. Should a change in color, consistency, material or the like be desired a second liquid unit containing the proper material may be instantly substituted without requiring any cleaning of parts whatsoever. A simple rubber or cork stopper fitted over the nozzle 54 of the removed unit will serve to prevent evaporation and hardening of the material in the fine bore 55 of its nozzle. Obviously materials of different consistency will be placed in containers having nozzle bores of proper caliber. The air unit of the gun is never contaminated with any liquid and does not require cleaning. The containers can be shifted so quickly that high volatile paints already sprayed on a surface do not have time to dry before a second color, which it is desired to blend with them, is ready for application, whereas with the old type of gun the time necessary for cleaning the containers, eduction tubes and the like precluded this type of operation without using two complete guns and then there was the opportunity for paint in the first one used to harden in the nozzle and tubes before the operator finished with the second and got around to cleaning it.

The gun of the present invention is simple in construction, low in cost, simple to operate and produces just as good results as the more complex and costly guns which cannot be used for a new color or material without time consuming cleaning.

I claim:

1. In a spray gun, in combination; an air control unit comprising a handle having an air passage therein, a spring closed valve in said handle to control said passage, a trigger for opening said valve, a forward extension from said handle, an air jet supported by and substantially parallel to said extension, flexible conduit means connecting said jet to the valve controlled portion of said passage; a self-contained spray-liquid unit comprising support means removably interengaged with said forward extension and connecting said units mechanically, a nozzle carried by said support means with its axis substantially normal to the axis of said jet, said nozzle being positioned just below the jet axis for spraying, an eduction tube carried by said support means and connected to said nozzle, a container cover carried by said support means and a container for spray liquid removably carried by said cover in a position housing said eduction tube.

2. The spray gun combination as claimed in claim 1 in which means is provided to adjust the said air jet on said extension in the direction of the axis of the said nozzle to regulate the character of the spray pattern.

3. The spray gun combination as claimed in claim 1 in which said support means is interengaged with said forward extension along an axis generally in the direction

of the axis of said air jet for adjustment to regulate the character of the spray pattern.

4. The spray gun combination as claimed in claim 1 in which means is provided to relatively adjust the said air jet and nozzle in the direction of the axis of the air jet to regulate the character of the spray pattern.

5. The spray gun combination as claimed in claim 2 in which means is provided to relatively adjust the said air jet and nozzle in the direction of the axis of the air jet to regulate the character of the spray pattern.

6. The spray gun combination as claimed in claim 1 in which the interengaged means comprise parts relatively slideable in the general direction of the axis of the air jet whereby the tip of the latter may be advanced or retracted from the axis of the nozzle.

7. A spray gun comprising an air unit and a connected spray liquid unit selected from among a plurality of spray liquid units of different characteristics each adapted for use alone with the air unit: said air unit comprising a handle, an air jet supported by said handle, means to deliver air to said jet, and one part of a plug and socket connection having its axis substantially parallel to but below that of the jet; each spray liquid unit comprising a container for spray liquid, an eduction tube extending into said container, a nozzle of one of several different calibers connected to said eduction tube, the other part of said plug and socket combination being mounted on said container with its axis substantially normal to that of the nozzle; said plug and socket connection parts being so disposed in relation to the jet and nozzle that the axis of these elements substantially intersects at nearly 90°, and means on said handle to adjust the height of said jet above said nozzle.

8. The spray gun of claim 7 in which said connection parts are offset from the axis of the jet, means to prevent relative rotation between the gun units, and means to clamp the units throughout a range of plug and socket overlap to adjust the jet toward or from the nozzle axis.

9. The spray gun of claim 7 in which means is provided to effect relative adjustment of the air jet and nozzle in the direction of the axis of the nozzle to change the spray pattern.

10. The spray gun of claim 7 in which said socket is attached to project from said handle, a fitting adjacent the remote end of said socket having a vertical slot therein through which said jet extends, a spring urging said jet toward the top of said slot and a screw threaded through the fitting above the slot and having an end engaging the jet to adjust its position against the thrust of the spring.

11. The spray gun of claim 10 in which the fitting has a threaded opening remote from the slot, an extension of said opening in the socket wall and a screw engaged in 20 said opening to secure the plug in adjusted position in the socket.
